DESIGN FOR A GLASS GOBLET OR ARTICLE OF SIMILAR NATURE

Charles L. Fordyce, New York, N. Y., assignor to
Pitman-Dreitzer & Co., Inc., New York, N. Y., a
corporation of New York

Application December 13, 1944, Serial No. 116,881

Term of patent 14 years

(Cl. D36—8)

To all whom it may concern:

Be it known that I, Charles L. Fordyce, a citizen of the United States of America and a resident of New York, in the county of New York and State of New York, have invented a new, original, and ornamental Design for a Glass Goblet or Article of Similar Nature, of which the following is the specification, reference being had to the accompanying drawing forming a part hereof;

Figure 1 is an elevational view of a glass goblet, showing my new design; and

Figure 2 is an elevational view of the same taken at right angles to the disclosure in Figure 1.

I claim:

The ornamental design for a Glass Goblet or Article of Similar Nature, substantially as shown.

CHARLES L. FORDYCE.
